UNITED STATES PATENT OFFICE.

WALLACE S. TRINDER, OF SHREWSBURY, MASSACHUSETTS, ASSIGNOR TO PEERLESS MACHINERY COMPANY, OF BOSTON, MASSACHUSETTS, A CORPORATION OF MASSACHUSETTS.

EDGE GAUGE.

Application filed June 18, 1928. Serial No. 286,289.

This invention relates to edge gauges and while capable of general use is more specifically designed for use on skiving machines of the general character shown in United 5 States Letters Patent No. 220,906, to Amazeen, dated October 28, 1879 for Leather skiving machines.

In the shoe manufacturing industry, particularly, it is customary to skive the edges 10 of various parts of shoes in preparation of those edges either for edge folding or for seaming and in the former case, the skiving is deep while in the latter case it is comparatively shallow. In the use of skiving machines for doing this work, it is customary 15 to feed the work through the machine in contact with an edge gauge which may be set to regulate the depth of the skived surface and when a shoe part has skived edges of different depth, it is necessary to re-set the gauge whenever the depth of the skived edge is 20 changed. The re-setting of the gauge consumes time and effort on the part of the operator and if it has to be done frequently to 25 take care of the work as it comes to the skiving machine, the loss of time in the aggregate is considerable.

The main object of the invention is the provision of an edge gauge which may be used 30 for securing different depths of skiving without requiring any resetting of the gauge after its initial adjustment.

Another object of my invention is to provide a gauge having a plurality of edge guiding members which may be set at different 35 points to secure skiving of different depths so that the work may be fed through the machine in engagement with the edge guide which will give the depth of skiving desired.

Another object of the invention is the provision of a gauge having a plurality of guiding members of such form of construction as 40 to permit the work being passed through the machine in engagement with any one of the guiding members without encountering interference from the other guiding members.

A further object of the invention is to provide a gauge of simple form which is of a low cost of construction, which is efficient and 45 durable and which will not get out of order.

Other objects of the invention will be more specifically set forth and described herein-after.

My invention contemplates an edge-gauge 50 having a plurality of edge guiding members

capable of being adjusted independently of each other and so constructed that the work may be fed through the machine in engagement with the particular guiding member which will give the depth of skiving desired 60 without interference from the other guiding members. In one form of the invention, the guiding members are loosely supported over the work in a depending position and held in guiding position by gravity. This permits 65 the work to be fed under the guiding members when necessary, the members riding on the work and offering no obstruction to its passage through the machine.

In the drawings illustrating one form of 70 my invention, Figure 1 is a front elevation of the operative parts of a skiving machine of the construction hereinbefore referred to showing a gauge constructed and adapted to be operated in accordance with my invention 75 applied to said machine; Fig. 2 is a plan view of the gauge; Fig. 3 is an end view of the gauge looking from left to right in Fig. 1; Fig. 4 is a view in perspective of one of the guiding members reversed; Fig. 5 is a plan 80 view of a rectangular shoe part having skived edges of different widths and Fig. 6 is a cross-sectional view of the shoe part shown in Fig. 5 on line 6—6 therein.

Referring to the form of the edge gauge 85 shown in the drawings, 10 designates an elongated plate having at one end a curved guiding member 12 and adjacent the other end a longitudinal slot 14 whereby it may be adjustably secured in operative position on the machine. Mounted on the plate is a flat bar 16 having one end extended beyond the guiding member 12 and formed into a depending member 18 for holding down the work. The member 18 is in cross-section substantially 90 in the form of a quadrant of a circle (Fig. 3) with the curved portion presented toward the operator for facilitating the presentation of the work to the machine. The bar 16 at one end is held in position on the plate 10 by 95 a thumb screw 20 threaded into the slotted end of said plate and adjacent its guiding member end by an upright screw 22 in said plate. At its former end the bar 16 is tightly clamped to the plate 10 but at its latter end 100 it is free to yield when thicker portions of the work pass under the depending member 18. A helical spring 24 is mounted on the upright screw 22 and is held under compression by a loose washer 26 and a thumb 105 screw 28. The slot 14 is provided with a 110

nut 28 threaded on the upper end of the screw, which spring tends to hold the bar 16 downwardly while permitting it to yield when required. To adjust the bar vertically 5 to regulate the position of the hold-down member 18 an adjusting thumb screw 30 is threaded through the bar 16 adjacent the screw 22 with its end bearing against the plate 10 and by turning the screw 30 the 10 bar 16 may be raised or lowered at that end. The adjusting screw limits the downward movement of the bar and hold-down member but does not prevent them from yielding under the impact of thicker portions of 15 the work. When uniformly thick work is being fed through the machine, it is of advantage to set the hold-down member slightly higher to avoid undue pressure on the work. A set nut 32 serves to hold the 20 adjusting screw locked in adjusted position.

For providing one or more guiding members in addition to the main guiding member 12, a second flat bar 34 is mounted on the bar 16 and is provided with three slots (Figs. 25 1 and 2) for receiving loosely the screws 20, 22 and 30 and for permitting the bar 34 to be moved longitudinally in one direction or the other for purposes of adjustment. The free end 36 of the bar is turned up and carries a vertical socket 38 for holding a guiding member 40 loosely. The socket may be formed in any suitable manner but as shown is in the form of a vertical plate having its 30 two sides turned around to enclose the sides 35 of the guiding member. The upper portion 42 of the latter is thickened to form a shoulder 44 for engaging the top of the socket to limit its downward movement and its lower portion is cut away to leave a depending 40 guide proper 46 which is rounded on that side toward the operator to facilitate the passage of the work through the machine. The guiding member being loosely mounted in the socket and held in a lowermost position 45 by gravity alone the work passes under it without obstruction when the guiding member 12 is being used as the edge gauge and the member 46 then rides on the work.

In the drawings the edge gauge is shown as 50 adapted to a skiving machine of the type hereinbefore referred to in which 50 indicates a skeleton cutting disk held on the end of a cutter shaft 52 between an inner disk 54 fastened to said shaft and an outer disk 55 56 secured by a screw (not shown) threaded into the end of said shaft.

Mounted on a shaft 60 is a feed roll 62 which cooperates with a feeding disk 64 carried by a shaft 66 to feed the work; the two 60 shafts being substantially perpendicular to each other. The periphery of the feed roll is provided with an oblique feeding surface 68 having diagonal corrugations to grip the work. For a more complete description of 65 the parts of the skiving machine, their mode

of operation and functions, reference may be made to the said Amazeen patent hereinbefore referred to.

In applying the edge gauge to said skiving machine, the plate 10 is fastened by a screw 70 to a bracket 72 in turn secured by a screw 74 to a part 76 of the frame of the machine. A slot 78 in the bracket for receiving the screw 74 permits of a vertical adjustment.

In the use of my edge-gauge, the gauge as 75 a whole is first adjusted vertically on the machine by adjusting the bracket 72 vertically on the frame 76 of the machine and then the gauge is adjusted longitudinally on the bracket by manipulation of the plate 10 when the screw 70 is loosened. In making this latter adjustment the guiding member 12 is positioned to give the material the extreme depth of skiving. The bar 34 is then released by loosening the three screws 20, 28 80 and 30 and the set nut 32 and is moved longitudinally in one direction or the other to bring the guiding member 40 into exact position to serve as an edge-gauge for work to be skived a lesser depth. When so adjusted, the 85 screws are tightened. By the foregoing adjustment the work may be presented to the machine and fed therethrough using either the guiding member 12 or the guiding member 40 as an edge gauge. When the former is 90 used the latter rides on the work and performs no function, and since it is loosely mounted in the socket it offers no obstruction to the passage of the work and does not mark or deface it. 100

In the operation of the machine, the work to be skived is fed into the machine under the hold-down member 18 with its edge in engagement with the guiding member 12 or member 40 dependent upon whether a deep or 105 a shallow skiving is desired. The shaft 52 is set at an angle and the cutting disk lies in a plane slightly inclined to a horizontal plane which angle determines the obliquity of the skived edge of the work. 110

In Figures 5 and 6 is shown a rectangular shoe part 80 having two of its edges 82 provided with deep skiving and the other two edges 84 with shallow skiving. In operating upon such a part, the operator feeds the 115 work on the two sides 82 against the guiding member 12 and on the two sides 84 against the member 40 thereby skiving all the edges of the part 80 in one continuous operation. Heretofore, when but one guiding member 120 was provided, constant changes of the edge gauge were required to take care of variations in the depth of skiving, which changes consumed time and effort and interfered with the progress and continuity of the work. 125

If desired, one or more additional sockets may be mounted on the bar for accommodating one or more guiding members where more than two depths of skiving are required in the same piece of work but as a rule an edge 130

gauge having two guiding members will be found sufficient.

It is to be understood that my invention may be embodied in other forms of construction than that herein shown and described all within the scope of the following claims.

What I claim is:

1. An edge gauge for skiving machines comprising an elongated plate slotted at one end and provided at the other end with an edge guiding member and adapted to be adjustably mounted on a skiving machine, a flat bar mounted on said plate and adjustable longitudinally thereof, a socket carried by said bar and a second edge guiding member loosely mounted in said socket and adapted to ride on the work when said first guiding member is used as the edge gauge.
2. An edge gauge comprising a plate slotted at one end for adjustable mounting and having its other end turned laterally to form an edge guiding member, a bar carried by said plate and longitudinally adjustable thereon, a vertical socket mounted on one end of said bar and an edge guiding member loosely mounted in said socket and adapted to ride on the work when said first mentioned edge guiding member is in use.
3. An edge gauge comprising a plate slotted at one end for adjustable mounting and hav-

ing its other end in the form of an edge guiding member, a bar carried by said plate and longitudinally adjustable thereon and having one end extending beyond said plate guiding member, a vertical socket mounted on said end of said bar and an edge guiding member loosely mounted in said socket and adapted to ride on the work when it is in engagement with said first guiding member.

4. An edge gauge comprising an elongated plate slotted at one end for adjustable mounting and having its other end in the form of an edge guiding member, a bar adjustably mounted on said plate and having one end extending over and beyond said edge guiding member, a vertical socket mounted on said extending end of said bar and a second edge guiding member loosely mounted vertically in said socket and having an enlarged head adapted to engage the top of said socket for limiting the downward movement of said edge guiding member in said socket; said second guiding member being held in a lowermost position by gravity alone and being adapted to ride on the work when it is being guided by said first edge guiding member.

In witness whereof, I hereunto set my hand this thirteenth day of June, 1928.

WALLACE S. TRINDER.
